UNITED STATES PATENT OFFICE.

CHARLES WOOD McDONALD, OF SAN FRANCISCO, CALIFORNIA.

TELEGRAPH CODE.

No. 841,885.

Specification of Letters Patent.

Patented Jan. 22, 1907.

Application filed July 26, 1905. Serial No. 271,367.

To all whom it may concern:

Be it known that I, CHARLES WOOD McDONALD, a citizen of the United States of America, and a resident of San Francisco and State of California, (whose present post-office address is Manila, Philippine Islands,) have invented new and useful Improvements in Telegraph Codes, as set forth in the annexed diagrams and the following specification.

This invention relates to telegraph codes, and has for its object the provision of a code which is simple and capable of being readily and easily understood and operated and by which secret or cipher messages of one or more words or sentences may be prepared, transmitted, received, and translated expeditiously and accurately.

Other objects of the invention will appear more fully hereinafter.

The invention consists, substantially, in the construction, combination, location, and arrangement of parts, all as will be more fully hereinafter set forth, as shown in the accompanying drawings, and finally pointed out in the appended claims.

Referring to the accompanying drawings, and to the various views and reference-signs appearing thereon, Figure 1 is a view in diagram of a sheet or page constructed and arranged in accordance with and embodying the principles of my invention. Figs. 2 and 3 are similar views of other sheets or pages illustrative of the principles of my invention.

In transmitting secret or cipher messages by means of private or secret codes it is a common practice to employ arbitrarily-chosen prearranged words each designed to mean one or more words or a sentence of the message to be transmitted. This plan necessitates the use of a very large number of arbitrarily-chosen prearranged words if the code is designed to cover a desirable range of requirements and besides requires the greatest of care in arranging the code-words to form the message to be transmitted and in translating the message when received. Moreover, where an extensive code is employed the liability of making errors and mistakes is very great, since the variation in a single letter may cause a difference in meaning of an entire sentence. Such a practice is also open to the objection of great expense in transmitting a message telegraphically, since each message will be composed of several code-words, and which are charged for

either by the word or else by the number of letters employed.

It is among the special objects of my present invention to avoid the objections noted and to provide a code which, while simple and easily comprehended, will enable even extensive messages to be prepared, transmitted, received, and deciphered expeditiously and accurately and at small expense, while at the same time not sacrificing anything of secrecy.

It is also among the special purposes of my invention to provide a secret code or cipher which is practically unlimited in the extent or scope to which it may be applied.

In carrying out my invention I propose to employ a series of sheets or pages and to divide each sheet or page by ruling or printing lines thereon, or otherwise, into intersecting columns, thereby providing on each page or sheet as many separate spaces or subdivisions as there are columns extending in one direction multiplied by the number of columns extending in the other direction. In each of these spaces or subdivisions I propose to arrange one or more figures, words, or sentences, according to the circumstances, conditions, or requirements of the parties employing the code. Thus each firm, corporation, or individual may arrange the figures, words, or sentences according to the particular line of business in which the code is to be used, and hence codes embodying my invention may differ from each other in the character of the message to be sent, according to the will or desire of the ones employing the same. I also propose to provide distinguishing marks or characters for each column. These column-distinguishing marks or characters may be varied, altered, or changed as desired. For instance, they may be numerals, or they may be letters of the alphabet of the English or any other language, or they may be of any other desired distinguishing character. In the particular form shown, but to which, however, I do not desire to be limited or restricted, letters of the alphabet of the English language are employed. It is desirable that the columns of spaces or subdivisions extending in one direction be distinguished from those running in the opposite direction. Thus in the example illustrated in the drawings the horizontal columns are designated, respectively, by the consonants, while the vertical columns are designated, respectively,

by the vowels. Where all the letters of the alphabet are employed in the manner above indicated with the horizontal columns respectively designated by the consonants and the vertical columns by the vowels, it will be readily seen that each page or sheet will contain one hundred and five spaces or subdivisions each designed to contain one or more figures or words or sentences of the secret code. It is obvious that any desired number of sheets or pages may be employed. Where more than one page or sheet is employed, I propose to employ page or sheet distinguishing marks, figures, or characters.

15 In the particular form shown, to which, however, the invention is not to be limited or restricted, I employ letters of the alphabet to distinguish the sheets or pages from each other. Thus in the upper left-hand corner 20 of each sheet or page is placed the sheet or page distinguishing letter. If all the letters of the alphabet are employed for this purpose, it will be readily seen that two thousand seven hundred and thirty places or subdivisions are provided for the code. It is evident, however, that other or additional page or sheet distinguishing characters or marks may be employed. In accordance with my invention I propose to employ a transfer mark, figure, letter, or other character to indicate the particular page or sheet to which the column or page distinguishing mark employed in a message applies and indicating a transfer from one page to another.

35 In practice the transfer character is usually prefixed to the column or page designating characters employed in the message. If desired and in the case illustrated in the present instance, I propose to reserve one or 40 more letters of the alphabet to be employed as transfer-letters. Thus the letter "Z" as indicated by the expression "Transfer Z" above the spaces marked "Sheet A," "Sheet B," and "Sheet B A" on the drawings may be reserved for use only as a transfer-letter, indicating that a transfer is to be made from one page to another, and in which case said letter will not be used for column nor page identification purposes. Similarly, the letter 45 "Y" may also be reserved for the same purpose or for the purpose of denoting a new series of sheets or pages. By reserving two letters from the alphabet for denoting transfers and new series it will be understood that 50 each page or sheet will contain ninety-five sections or spaces each adapted to contain one or more figures, numerals, words, or sentences making up the code book or system and with twenty-four sheets or pages each 55 designated or identified by a separate letter of the alphabet a total of two thousand two hundred and eighty of such spaces and sections will be provided. Ordinarily I have found that a sufficiently large system for 60 practical purposes will be produced by re-

serving only one letter from the alphabet to denote transfers from one page to another—say, for instance, the letter "Z"—employing the remaining letters of the alphabet in the manner above described. This will result in 70 providing twenty-five pages or sheets each containing one hundred sections or spaces, or a total of twenty-five hundred spaces or sections.

As above indicated, each space or section 75 of each sheet or page is designed to contain one or more figures, numerals, words, or sentences, and these may be selected and arranged according to the desires or wishes of the individual making up the system. It will 80 also be seen that the particular arrangement and relation of the column and page or sheet identification or distinguishing characters may be varied for each particular system, as may be desired by the maker or user. A 85 convenient arrangement is shown wherein the consonants of the English alphabet are arranged in consecutive order along the marginal side or edge of each sheet or page, while the vowels are similarly arrayed along 90 the top of the page or sheet, and the pages are consecutively distinguished by the letters of the alphabet placed in the upper left-hand corner of the sheets or pages, and each sheet or page, if desired, may be conveniently ruled 95 according to the column arrangement of the letters, so as to divide such sheet or page into separate sections or spaces. These details, however, may be varied throughout a wide range without departure from the spirit 100 and scope of my invention, and I do not desire to be limited or restricted to the particular arrangement shown and described.

In order to make up a code-message in accordance with my invention, the desired 105 communication is selected from the various spaces or sections of the various pages, the use of a couplet of letters, a vowel and a consonant, indicating the particular section or space of a sheet or page and the page-distinguishing letter being employed as a prefix, the transfer-letter being inserted at the proper point to indicate a transfer from one page to another. Thus suppose the message received was as follows: "McDonald, Manila, 110 Aehzabok." The translation thereof will be effected by the use of the code-book as follows: The letter "A" indicates the first sheet or page, "eh" the section or space on said page at the intersection of the columns 115 respectively designated by the letters "E" and "H." In this space or section is found "Petition for patent does not infringe." The letter "Z" denotes a transfer to another page. The letters "b a" denote the 120 page to which the transfer is made, the letters "o k" the particular space or section on said page containing the remaining part of the message, as follows: "upon anything 125 on file in this office," so that when translated 130

the complete message will read: "McDonald, Manila, Petition for patent does not infringe upon anything on file in this office." In similar manner messages may be prepared for transmission, as will at once be apparent to those skilled in the art.

From the foregoing description, taken in connection with the accompanying drawings, it will be seen that I provide an exceedingly simple code system by the use of which messages may be expeditiously prepared, transmitted, received, and translated without error and at small expense and that the system may be made as large or as small in range as may be desired.

Having now set forth the object and nature of my invention and a construction embodying the principles thereof and having explained the principles thereof and the best mode in which I at present contemplate applying the same, what I claim as new and useful and of my own invention, and desire to secure by Letters Patent, is—

1. A telegraph code comprising a series of sheets or pages each divided into sections or spaces arranged in intersecting columns, each space adapted to contain one or more figures, numerals, words or sentences, each column and each page having a distinguishing character and a transfer character to denote transfer from one page to another.

2. A telegraph code comprising a series of sheets or pages each having a distinguishing or identifying character, and each divided into sections adapted to contain one or more numerals, words or sentences, said sections being arranged in intersecting horizontal and vertical columns, an identifying or dis-

tinguishing character, associated with each column at one end thereof, and a transfer character to denote a change or transfer from one sheet or page to another.

3. A telegraph code comprising a series of sheets or pages respectively distinguished by letters of the alphabet, each sheet or page having sections or spaces arranged in intersecting columns, the columns running in one direction being respectively distinguished by certain letters of the alphabet and those running in the opposite direction being distinguished by other letters of the alphabet, each section or space adapted to contain one or more numerals, words or sentences, and a character differing from those employed to distinguish the sheets or pages and columns to denote transfer from one page to another.

4. A telegraph code comprising a series of sheets or pages respectively distinguished by identifying characters, each sheet or page having sections or spaces arranged in intersecting columns, the columns running in one direction being respectively identified by the vowels of the alphabet, and the columns running in the opposite direction being distinguished by consonants, each section or space adapted to contain one or more numerals, words or sentences, and a transfer character to denote transfer from one page or sheet to another.

In testimony whereof I have signed my name to this specification in the presence of two subscribing witnesses.

CHARLES WOOD McDONALD.
